Primary Examiner — Lauren R Calve(74) *Attorney, Agent, or Firm* — The Law Office of
Patrick F. O'Reilly III, LLC(57) **CLAIM**

The ornamental design for an ergonomic grip, as shown and described.

DESCRIPTION

FIG. 1 is a top-side perspective view of an ergonomic grip showing my new design;

FIG. 2 is a front elevational view of the ergonomic grip shown in FIG. 1;

FIG. 3 is a right side elevational view of the ergonomic grip shown in FIG. 1;

FIG. 4 is a rear elevational view of the ergonomic grip shown in FIG. 1;

FIG. 5 is a left side elevational view of the ergonomic grip shown in FIG. 1;

FIG. 6 is a top plan view of the ergonomic grip shown in FIG. 1;

FIG. 7 is a bottom plan view of the ergonomic grip shown in FIG. 1; and,

FIG. 8 is a bottom-side perspective view of the ergonomic grip shown in FIG. 1.

The broken line portions of the drawing figures are included to show unclaimed subject matter only and form no part of the claimed design.

1 Claim, 5 Drawing Sheets(56)
